STEREOTYPE PLATE CASTING MACHINE

Paul L. Tollison, North Plainfield, Charles L. Ricards, South Plainfield, and Paul J. Schkeeper, Plainfield, N.J., assignors to Wood Newspaper Machinery Corporation, Plainfield, N.J., a corporation of Virginia

Filed June 6, 1961, Ser. No. 115,145
11 Claims. (Cl. 22—3)

This invention relates to a stereotype plate casting machine and more particularly to a stereotype plate casting and finishing machine for making newspaper printing plates.

Stereotype plate castings used in newspaper presses must be cast quickly and without any blemishes on the type surface because of gas evolving from the molten metal as it solidifies. Usually the plate is cast with the tail portion at the top of the plate as it lies in the mold cavity so that gases may rise into this portion and also to provide a sufficient reservoir of molten metal to counteract for shrinkage of the casting as it solidifies. The tail portion is then severed from the casting and the cut edge of the remaining plate portion of the casting beveled so that it may be fitted onto a printing cylinder. In addition, recesses are often milled on the underside of the plate so that the plate may be locked onto the printing cylinder by plate locking clamps mounted on the cylinder.

It is desirable for the ports comprising the mold cavities of the machine to be controllably cooled in order that a maximum number of plates may be cast in a minimum amount of time under proper temperature conditions. It is further desirable that the complete machine be as automatic in operation as possible in order to reduce labor expense and the necessity of manually handling hot castings. It is further desirable that the machine have safeguards to prevent inadvertent jamups of plates as they move from the casting station on to the other finishing stations.

It is, therefore, an object of our invention to provide for a plate casting and finishing machine in which the steps from the act of casting until the plate is completely finished and cooled and ready for removal to the pressroom are completely automatic.

A further object of our invention is to provide for a plate casting machine which will operate at a high rate of production and which will be able to rapidly cool molten metal in the mold in order that castings may be moved to finishing stations.

It is a further object to provide for means which will automatically move plates from a shaving arch wherein the tail is severed from the plate so doing away with manual handling of the hot plate. Still a further object is to provide means whereby severed tails and defective plates may be ejected from the casting machine and returned to a melting pot.

An additional object of our invention is to provide a safety stop means whereby a plate will be prevented from inadvertently entering a milling station in which recesses are milled while another plate is still in the station.

Broadly, we propose to provide for a plate casting and finishing machine which has a casting station, a shaving station, an ejection station, a milling station, and a cooling station. The casting station comprises a movable core which cooperates with a movable box to form a mold cavity. The core has therein circulating passages through which a circulating cooling fluid may flow to provide an even cooling over the entire surface of the core adjacent to the mold cavity. In particular, the core has therein a manifold separated from the core body by a cooling section. The manifold has an inlet for the admission of a cooling fluid and a plurality of jets so that the cooling fluid may be sprayed into the cooling section

2

onto the wall of the core forming a side wall of the mold cavity. Discharges are placed at the bottom of the cooling section and the total cross-sectional area of the discharges is greater than the inlet in order to insure complete removal of water from the core when the inlet is closed.

Core rotation means are provided for rotating the core to a horizontal position where pusher means may then push the casting into the shaving station. In the shaving station, the tail is severed from the casting and the severed edge trimmed by conventional means.

Propeller means are provided in the shaving station for moving the cast plate out of the station. The propeller means comprises a rotatable lug mounted on a lug carriage. The lug carriage in turn is slidably mounted in tracks on a rotatable knife bar which carries thereon a cutting saw for severing the tail section from the casting and knives for beveling the severed end of the casting. The carriage is connected to a drive chain which in turn is intermittently driven by the rotatable knife bar.

Powered rollers are provided to carry the severed tail from the shaving station to an ejection station and also to move the plate after it is moved out of the shaving station by the propeller means.

The ejection station of the casting machine has a pivotable arm therein which pivots underneath a severed tail to throw the tail from the machine onto a conveyor which returns it to the melting pot. The pivotable arm also has a control so that the arm may be actuated to eject a defective plate from the casting machine.

Incline means are provided between the ejection station and milling station for moving the plate to the milling station. Safety stop means are positioned between the ejection station and the milling station on the incline means to prevent inadvertent entry of a plate in the milling arch while another plate is being milled in the arch. The safety stop means comprises two retractable stops moved by the miller drive means in the milling arch and which operate so that when one stop moves out of the path of a plate moving into the arch, the other stop will move up so that the plate may move down the incline means to the arch only when both stops are in a retracted position.

Referring to the drawings in which a preferred embodiment of our invention is shown,

FIG. 1 is a front partial sectional view of a complete plate casting and finishing machine constructed according to our invention;

FIG. 2 is an enlarged view of FIG. 1 taken along lines 2—2 illustrating conveyor means for removing chips from the machine to a second conveyor which returns the chips to a melting pot;

FIG. 3 is an enlarged cross-sectional view of a core and casting box of the machine of FIG. 1 shown in the casting position;

FIG. 4 is a cross-sectional view of a core of FIG. 3 taken along lines 4—4;

FIG. 5 is a cross-sectional view of the core of FIG. 3 taken along lines 5—5;

FIG. 6 is a rear view of a portion of the machine of FIG. 1 illustrating pusher means for moving the plate from the core into a shaving station;

FIG. 7 is an enlarged view of a portion of the end of the machine of FIG. 1 taken along lines 7—7;

FIG. 8 is an enlarged sectional view of the machine of FIG. 1 illustrating the propelling means for moving a plate out of the shaving station;

FIG. 9 is a view similar to FIG. 8 showing the exit end of the shaving station;

FIG. 10 is a broken plan view of the shaving station of FIGS. 8 and 9 with the shaving arch removed;

FIG. 11 is an enlarged cross-sectional view of the propeller arm shown in FIG. 8 taken along lines 11—11;

FIG. 12 is a cross-sectional view of the knife bar and tail cutter assembly taken along lines 12—12 of FIG. 9;

FIG. 13 is an enlarged end view of the differential gear assembly illustrated in FIG. 9 taken along lines 13—13;

FIG. 14 is an enlarged side sectional view of the shaving arch clamping drive means and of a part of the propeller arm drive means;

FIG. 15 is a cross-sectional view of FIG. 14 taken along lines 15—15;

FIG. 16 is a partial cross-sectional view of FIG. 14 taken along lines 16—16 illustrating the shaving arch lockup means;

FIG. 17 is a partial cross-sectional view of FIG. 14 taken along lines 17—17 illustrating a part of the propeller arm drive means;

FIG. 18 is a partial cross-sectional view of FIG. 14 taken along lines 18—18 and illustrating the ejector arm mechanism;

FIG. 19 is an enlarged cross-sectional view of FIG. 16 taken along lines 19—19;

FIG. 20 is an enlarged cross-sectional view of FIG. 16 taken along lines 20—20;

FIG. 21 is an enlarged cross-sectional view of FIG. 17 taken along lines 21—21;

FIG. 22 is an enlarged cross-sectional view of a portion of FIG. 1 illustrating the safety stop means for preventing inadvertent entry of a plate in the milling station;

FIG. 23 is a plan view of the structure illustrated in FIG. 22;

FIG. 24 is a cross-sectional view of the structure of FIG. 22 taken along lines 24—24; and,

FIG. 25 is a cross-sectional view of FIG. 22 taken along lines 25—25.

Referring in greater detail to the drawings and in particular to FIG. 1, 1 denotes generally a stereotype plate casting machine having a casting station 200, a shaving station 300, an ejection station 500, a milling station 600, and a cooling station 700.

The casting station comprises a melting pot 202 in which metal may be melted so that it may be pumped by conventional pumping means through the spout 204 from where it may drop into a mold cavity 206 formed by a movable casting box 208 and a movable casting core 210 as shown in FIG. 3. The casting box 208 has therein a suction space 212 which is connected by means of a conduit 214 to a suction pump (not shown) in order that a mat M may be securely held therein. The box, which is movable laterally by means not shown, has a cooling section 216 through which coolant may be circulated.

The core 210 has therein a cooling section 218 and a manifold section 220. An inlet passage 222 communicates with a flexible hose 224 through which cooling water may flow into the manifold 220. A plurality of ports or nozzles 226 extend through a wall of the manifold into the cooling section 218. At the bottom of the cooling section 218 are discharge passages 228 and 233 through which the cooling water is discharged from the cooling section. A flexible hose 231, which connects with discharge passage 228, extends onto the shaving arch so that a portion of the cooling water passing from the core is also used to cool the shaving arch. The nozzles 226 near the bottom end of the manifold are spaced closer together than at the top so that more water may be passed into the lower portion of the cooling section than in the upper portion of the cooling section. This is so that the cooling of the core will be even along its length since molten metal flowing into mold cavity 206 from the spout 204 will initially fill the bottom of the cavity so that the bottom of the mold will tend to be hotter than the top if no provision were made to provide extra cooling. The total area of the discharge passages 228 and 233 is greater than that of the inlet passage 222 to insure that no water will remain in the cooling section after the inlet is closed by a solenoid-operated valve (not shown) before the core is rotated. The core must be emptied of water before

a plate is cast otherwise the core would become too cold which would produce a defective casting.

The core 210 is rotatable to a horizontal position by means of a hydraulic actuator 230. The actuator 230 has a movable rod 232 which connects to an arm 234 which is rotatable about a shaft 236. An arm 238 is integral with arm 234 and is connected by a link 240 to the core 210. The core is partially supported in a vertical position by means of an arm 242 which is pivotable about a point (not shown).

The core and box are moved in a manner and by the apparatus as shown in application Serial No. 802,481, filed March 27, 1959, by P. L. Tollison and C. L. Richards, now Patent No. 3,052,933 issued Sept. 11, 1962. In order to cast a plate, the box is first moved horizontally away from the core to a tilted position wherein a mat may be easily and accurately positioned in the box after which the mat is clamped into the box by mat clips (not shown). The box is then tilted to the vertical position or mat stripping position and moved horizontally to the casting position as shown in FIG. 3 wherein it forms with the core 210 a mold cavity. While the box is in the mat stripping position, the core is in a horizontal position and rotates to the vertical before the box moves to the casting position. Molten metal is then pumped from the melting pot 202 through spout 204 so that it falls into the mold cavity. After the metal has solidified, the casting box is moved horizontally to the mat stripping position after which the core is rotated to a position as shown in FIG. 6 where the plate is lifted by plate lifters (not shown) from the core.

When the casting has been lifted off the core, a pusher arm 250 as shown in FIGS. 6 and 7 is rotated by a hydraulic actuator 252 about a shaft 254 so that a contact shoe 256, carried on the end of the arm, will extend down and behind the casting as shown in FIG. 7. The pusher arm, shaft, and actuator are all carried by a bracket 258 in turn carried by a bar 260 extending parallel to the longitudinal axis of the machine. The bracket 258 is prevented from turning about the rod 260 by means of a square bar 262 which extends parallel to and below bar 260. The bracket has a plate 264 which extends behind the bar to prevent the bracket from rotating about the bar 260.

The pusher arm is provided with two limit switches 266, only one of which is shown in FIG. 7, operated by cams 268 and 270 which operate solenoid valves to control admission of pressure fluid to actuator 252.

The bracket 258 is moved longitudinally of the machine by means of a double acting transfer actuator 272. A chain 274 connects at one end to the actuator 272 and at the other end with a piston rod 276 while meshing with cogs 278 and 280. Application of pressure to either end of the actuator will cause the piston rod to move and rotate a shaft 281 on which cog 278 is mounted. A drive cog 282, which is also mounted on shaft 281, will rotate so moving a chain 283 and bracket 258.

As the pusher arm approaches the shaving station 300 and is clear of the core 210, the bracket will contact a limit switch 284 which will activate a solenoid valve (not shown) to allow pressure to be applied to core rotation actuator 230 to return the core to the vertical casting position shown in FIG. 3. A limit switch 285 is activated by the bracket to cause reversal of hydraulic pressure in actuator 272 and thus serves to limit movement of the casting into the shaving station and to return the pusher arm to the start position.

As the bracket clears the shaving station 300, it will activate a switch 286 which will operate a solenoid valve to cause hydraulic pressure in actuator 252 to raise arm 250. As the bracket reaches the extreme limit of its travel to the left as shown in FIG. 11, it will contact a further limit switch (not shown) which causes a bleed-off in pressure in actuator 272 thus stopping the pusher arm in the correct position to again remove a casting from the core.

The complete pushing operation is begun when the core on reaching the retracted or horizontal position activates a limit switch (not shown) to cause pressure to be admitted to the actuator 252 to cause the arm to drop.

Referring to FIGS. 8 and 9, there is shown a shaving arch 301 having means for severing a tail portion T of a plate casting P along with means for moving the plate out of the shaving arch. A plate is initially positioned in the shaving arch by means of the plate pusher arm 250 as previously explained and until cast lugs L, which are cast onto the tail portion of a plate as shown in FIG. 10, contact adjustable stops 303 as shown in FIG. 12. The stops 303 are adjustable and are attached to a rotatable knife bar 302 which is journalled in bearing assemblies 304 and 305 carried in the frame of the casting and finishing machine. The knife bar is rotated by a worm gear 307 connected to a drive means (not shown).

After the plate has been positioned in the shaving arch 301, it is ready to be lifted and clamped to the underside of the arch so that the tail may be severed and the severed edge beveled.

Referring to FIGS. 9, 14, and 16, it is seen that a drive gear 306 mounted on the rotatable knife bar 302 meshes with a clamp-up gear 308 which is keyed to a cam shaft 310 journalled in bearings 313 and 315 mounted in the frame of the casting and finishing machine. Cam shaft 310 has thereon a cam 312 on which a cam follower 314 is mounted on a yoke 316. Yoke 316 in turn is connected to an arm 318 which is mounted on a rotatable shaft 320. Shaft 320 also has thereon an arm 322 connected to a further arm 324 which has on the end thereof a foot 326 on which one end the plate rests. The other end of the plate rests upon a track 327 so that the plate is supported by the track 327 and foot 326 while in the shaving station. A spring 317 urges the cam follower 314 into close contact with the cam 312 at all times. It is seen that when the cam shaft 310 is rotated, as the cam follower hits the high part of the cam, it will cause the arm 322 to rotate in a counterclockwise direction as shown in FIG. 16 to raise the foot 326 and so raise the plate casting P until it securely abuts the underside of the shaving arch.

A saw 330, as shown in FIGS. 8, 9, and 12, is rotatably mounted in a saw body 332 which in turn is mounted on the rotatable knife bar 302. The saw 330 is rotated in the saw body by means of a saw drive shaft 334 through gears 336, 338 and 340. The saw drive shaft 334 in turn is driven by a belt drive 342 connected to a drive means (not shown).

Also mounted on the rotatable knife bar are knives 344 and 346 which serve to cut a bevel 348 on a plate P and to shave the ribs inside the plate after the tail portion T has been severed from the plate by saw 330. After the tail has been severed it will drop down on powered rollers 350, FIGS. 22 and 23, which will carry the tail to the ejection station where it will be ejected from the machine and returned to the melting pot as more fully explained hereafter.

The propeller means for moving the cast plate, after the tail portion T has been severed therefrom, out of the shaving arch is best illustrated in FIGS. 8, 9, 10, and 11. The propeller means comprises a rotatable lug 360 which is mounted on a shaft 362 which in turn is carried by a carriage 364. The lug 360 has a torsion spring 366 which urges the lug upward so that it may contact the rear end of a plate to move the plate out of the shaving arch and so that a casting may pass over it when moved into the arch by the pusher arm 250. The carriage 364 slides in tracks or ways 368 which in turn are connected to a knife bar 302. The carriage 364 is connected through a narrow slot 370 in the ways 368 to a chain-operated carrier 372 by means of a pin 374. The chain-operated carrier 372 is slideable in ways 376 machined in the knife bar 302, and the chain-operated carrier is confined in the ways 376 by the ways 368 which also serve as a protective covering to prevent entry of metal chips, shavings, etc.

into the ways 376. The chain-operated carrier is connected by a pin 378 to a special link 380 which is a part of a chain 382. Chain 382 fits onto an adjustable sprocket 384 and to a drive sprocket 386. The adjustable sprocket 384 is slideable longitudinally of the knife bar in ways 388 machined in the cutter bar and is held in position in the ways by a clamp 390. By moving the sprocket 384, the tension of the chain 382 may be adjusted.

Drive sprocket 386 is driven by mitre gears 392 and 394 as shown in FIG. 9. Mitre gear 394 has an integral shaft 396 which extends outwardly of the knife bar 302 and has secured to its end a differential gear 398. Differential gear 398 in turn meshes with cluster bevel gears 400 and 402. Gears 400 and 402 are journalled in a spider 404 which is rotatable about shaft 396. An input gear 406 is a central member of the differential and is an integral part of the enclosing structure for the differential.

Referring to FIGS. 19 and 20, it is seen that a gear 408 is keyed to a differential bevel gear 410 which also meshes with gears 400 and 402. Gear 408 meshes with a pinion 412 which in in turn meshes with another pinion 414 as best shown in FIGS. 19 and 20. Pinion 414 meshes with drive gear 306 which is also used to actuate the plate clamping mechanism in order to clamp the plate up against the shaving arch 301.

Referring to FIGS. 14, 17, and 21, it is seen that gear 406 of the differential meshes with a gear 416 which in turn is keyed to a gear 418 journalled on cam shaft 310. Gear 418 meshes with an idler gear 420 which is engaged by a rack 422. Rack 422 may be moved by a double acting fluid actuator 424. Fluid pressure to actuator 424 is controlled by a solenoid-operated valve (not shown) controlled by a limit switch 426 and a cam-operated switch 428. A cam 430 is mounted on cam shaft 310 and will actuate switch 428 to cause hydraulic pressure to be admitted to the blind side of actuator 424 to move the rack 422 to the right as shown in FIG. 17. When rack 422 contacts limit switch 426, it will cause hydraulic pressure to be admitted to the rod end of the actuator 424 so causing the rack to move to the left as shown in FIG. 17.

During rotation of the knife bar 302, the propeller means 360 will tend to move and not be in correct position to receive a plate coming into the shaving arch 301 if provision is not made in the arrangement of the gearing to cancel out the planetary effect of the rotation of the knife bar and the relative position of the propeller means. In the illustrated arrangement of gearing, it will be evident from FIGS. 19 and 20 that when the knife bar rotates one revolution, gear 306, keyed to the knife bar, will cause gear 408 through intermeshing pinions 412 and 414 to also rotate one revolution but in an opposite direction to that of the knife bar. Gear 408, which is keyed to gear 410, will then cause gears 400 and 402 to rotate. If the spider 404 is locked from rotation by maintaining fluid pressure in actuator 424 and thus locking the rack 422 and gears 420, 418, 416, and 408 from movement, then gears 400 and 402 will cause the gear 398 and shaft 396 to rotate in the same direction as the knife bar 302 with no relative movement between them. Since there is no relative movement, the propeller arm 360 will remain stationary with respect to the knife bar.

The sequence of operation in propelling a plate out of the shaving arch is as follows: As the knife bar rotates and just before it stops, cam 430 will trip switch 428 setting up an electrical circuit so that when the knife bar stops rotating, the cam 430 will release the switch 428 to energize a solenoid valve (not shown) to divert a pressure fluid to the blind end of actuator 424. This will move rack 422 to the right as shown in FIG. 17 to rotate gears 420, 418, 416, and 406. Rotation of gear 406 and spider 404 will then cause gears 400 and 402 to rotate resulting in rotation of gear 398, shaft 396, gears 394 and 392 which drives the sprocket 386.

As the rack 422 contacts limit switch 426, the valve solenoid referred to above will be de-energized so allowing fluid pressure to be exerted on the rod end of actuator 424 to cause the rack and propeller to return to its starting position and allowing fluid pressure to be kept on the rod end to lock the rack in place.

Reference is made to FIG. 18 which illustrates an ejector means in the ejection station 500. An ejector arm 502 is rotatable about a shaft 504 when actuated by a hydraulic actuator 506. A plurality of spaced powered rollers 350 support the tail after it has been severed from the casting in the shaving station and move the tail to the ejection station. Fingers 503, mounted on arm 502, extend between the rollers 350 and are adapted to engage an edge of a plate. When pressure is applied to the blind end of actuator 506, the arm will be caused to rotate about shaft 504 to cause the tail to turn about one of its edges and to overturn onto a tail chute with sufficient momentum to carry it on to a moving conveyor belt 510 as shown in FIG. 2 which returns the tail to the melting pot.

The tail is cast with a protruding portion 512 which is engaged by a stop 514 mounted on the ejector arm so that the severed tail will not pass on from the ejection station. A cam 516 is mounted on the cam shaft 310 and is set to trip and hold a switch 518 which controls by means of a solenoid-operated valve (not shown) admission of pressure to the actuator 506. The dwell of cam 516 is so proportioned that before the knife bar 302 completes its shaving and trimming operation and comes to rest, switch 518 is again tripped to de-energize the valve solenoid (not shown) and divert fluid pressure to the rod end of the actuator 506 which will then return the ejector arm 502 to its down position so that it will not obstruct a plate being pushed out of the shaving arch. The ejector arm is held in the down position by fluid pressure in the actuator 506 and is designed to operate once during each revolution of the knife bar.

When it is necessary to reject a defective plate, such as the first plate cast in the cold casting station, stops 520 illustrated in FIG. 25 are moved to intercept the movement of the plate along the powered rollers 350 to hold the plate in position whereby the ejector arm may kick the plate out of the machine. Stops 520 are mounted on arms 522 connected to a rotatable shaft 524. The shaft 524 further has therein arms 526 which in turn are connected to a hydraulic actuator 528. The hydraulic actuator 528 is a single acting hydraulic actuator that moves in one direction by fluid pressure and in an opposite direction by a spring (not shown) in the cylinder. Application of hydraulic pressure by a solenoid-operated 3-way valve (not shown) to the blind end of the cylinder will cause stops 520 to retract to the position shown in FIG. 25 and allow plates to pass by the stops on the rollers 350 without interruption. Release of pressure from the blind end of the actuator 528 will cause the stops 520 to move into the path of a plate to stop it and will hold the plate in the correct position where the ejector arm can engage it and kick it out onto the chute 508 from whence it can be returned to the melting pot by a conveyor. While plate stops 520 are primarily for intercepting plates to be ejected, an arrangement of the present machine is to provide for a 3-way solenoid valve controlling admission of hydraulic pressure to the actuator 528 which is contained in the shaving motor electric control circuit so that the stops 520 will remain in the intercepted position through the complete shaving cycle and in the retracted position shown in FIG. 25 only when the shaving motor is de-energized. This will insure that in the event the tail stop 514 shown in FIG. 14 fails to stop the tail after it is severed from the plate and falls on the powered rollers 350, that the stops 520 will be in a position to stop the tail so that the tail cannot pass further on into the finishing machine and cause a jamup. The result is that stops 520 will normally go through a complete

cycle of operation on each revolution of the knife bar regardless of whether a tail or plate is ejected.

If for any reason it is desired to eject a plate, a push button 540 is provided as shown in FIG. 1 on the console 5 of the machine which when pushed will set up a circuit to de-energize the 3-way solenoid valve controlling admission of pressure to actuator 528 thus maintaining the stops 520 in their extended position to intercept a plate after it has been pushed out of the shaving station. Immediately before the plate is intercepted by the stops 520, it will contact a lever 551, FIG. 22, to a trip switch 552 to energize a solenoid valve (not shown) to divert fluid pressure to actuator 506 to eject the plate in the same manner as a tail is ejected. When the ejector arm 502 reaches the limit of its upward travel, a cam 554 mounted on shaft 504 trips switch 556 which operates a solenoid valve to divert pressure to the rod end of actuator 506 to cause the arm 502 to return to its retracted position. As explained more fully hereafter, tripping of the switch 556 sends an impulse to a counter so that the total plates produced on one run of the machine will not be affected by the rejected plate.

After a plate leaves the ejection station, it is conveyed by the powered rollers 350 to an incline means comprising free-running idler rollers 602 as shown in FIGS. 22 and 23 where the plate will proceed to move down the rollers into a milling arch 604 where recesses may be milled on the underside of the plate by millers 606. In order to prevent inadvertent entry of a plate into the milling arch while another plate is still in the arch, we provide a first and second retractable stop means 608 and 610 which are driven by a milling drive motor 612. Milling drive motor 612 is connected by means of a V-belt 614 to a pulley 616. Pulley 616 in turn is mounted on a worm 618 which then rotates worm gear 620 which is mounted on a worm 622. Worm 622 drives a worm 624 which is connected to a cam shaft 626.

Referring to FIG. 24, it is seen that cam shaft 626 activates plate clamping shafts 628 and 630 in a conventional manner through spring biased levers 632 and 634 connected by a link 636 to which is mounted a cam follower 638 adapted to follow cam 640. The shafts 628 and 630 may thus be rotated to raise lifting arms (not shown) which in turn will force the plate against the underside of the milling arch 604 to lock it firmly in place.

The powered rollers 350 of the ejection station are driven by a cross shaft 642 which connects the rollers by a drive chain (not shown) protected by a cover 644. Shaft 642 in turn is rotated by a worm shaft 646, mitre gears 648 and 650, a shaft 652, and mitre gears 654 and 656 which is mounted on shaft 622.

A feed cam shaft 658 is also driven by motor 612 through means of connecting gears 660, 662, and 664, the last of which is connected to shaft 626. A cam 666 mounted on shaft 658 contacts a cam follower 668 in turn mounted on retractable stop 610. Stop 610 is urged in an upward direction by springs 670 and 672 and is retracted by cam 666. The second stop 608 is controlled by a cam 674 on which a follower 678 rides and which is also urged in an upward direction by springs 670 and 672. The cam 666 is so contoured that stop 610 will remain in the up position during most of the time cycle and depressed only long enough to release the plate and then return to the up position to intercept the next incoming plate. The stop 608 remains in the retracted position during most of the time cycle to allow the incoming plate to pass on to stop 610. Cam 674 is so contoured to allow stop 608 to move to the up position only while stop 610 is depressed so as to insure that an incoming plate will not pass into the milling station while stop 610 is depressed and thereby cause a jam and damage the machine. To this extent, stop 608 is a safety stop.

In addition, the machine may be provided with screw-type conveyors 311 and 611 as shown in FIG. 1 which

convey chips and shavings from the shaving and milling stations to a central belt conveyor 613 which runs laterally of the machine and which conveys material to conveyor 510 which in turn runs back to the melting pot. The conveyors 311, 611, 613, and 510 may be driven by any convenient means.

The plate casting and finishing machine is provided with a console 50 as shown in FIG. 1 which has thereon the controls for starting and stopping the machine and a counter 51 by which the number of castings in a single run may be controlled.

The control circuits connecting the various limit switches, interlocks, electric drives, and solenoid valves is not illustrated since it is not necessary in order to understand the workings of the various parts of the plate casting and finishing machine.

Broadly the sequence of the operations of the complete device is as follows: Initially after the melting pot has been heated and the metal completely liquefied, a mat is inserted in the casting box while it is in the tilted position. After the mat has been clamped in the box and the number of plates desired to be produced set on the counter, the machine is started. The casting box will then move to the vertical mat stripping position and the core will move to the vertical position after which time the box will move towards the core to the casting position. A vacuum pump will then start up to put a vacuum in the casting box to tightly secure the mat in the box. When a predetermined vacuum is obtained, a solenoid valve will be actuated to start water circulating through the core and box. A molten metal pump will then be energized to cause molten metal to be pumped through the spout into the mold cavity. After a predetermined period of time, the metal pump will stop and the box caused to move to the mat stripping position where it will strip the mat from the core. The vacuum is released from the casting box and circulating cooling water in both the box and core is shut off. The core will then rotate to the horizontal position where the plate will be lifted from the core by plate lifters and be pushed into the shaving arch by the pusher means as previously explained. As the pusher means advances, it will activate a switch to cause the core to return to the casting position and so restart the pouring and casting cycle.

Inside the shaving arch, the plate will be clamped up so as to securely engage it against the underside of the shaving arch. The knife bar will then commence rotating so that the saw will sever the tail from the casting while at the same time beveling the severed edges of the casting. The above sequence of operations is the same as that set out in application Serial No. 802,481 previously referred to.

After the tail is cut, it will fall off onto the powered rollers 350 from where it will be carried to an ejection station 500. After hitting a stop 514 mounted on arm 502, the ejector arm will then rotate upwards as previously explained to eject the tail from the station. After the ejector arm has retracted and the knife bar rotation stopped, a propeller means will push the plate from the shaving station onto the powered rollers 350 from whence it will be moved to the incline rollers. The plate will then move by gravity into the milling station 600 provided there is no plate in the station and the stops 608 and 610 do not prevent entry of the plate into the milling station. In the milling station, the plate will then be clamped up onto the underside of the milling arch after which recesses or notches are milled into the bottom side of the plate. From the milling station, the plate goes on to the cooling station 700 where the plate may be cooled by conventional water sprays and air jets. From the cooling station, the plate may pass on by roller conveyors to a storage area.

The circuitry of the machine is set up so that the first plate cast on any run is automatically ejected by the ejection station. This is because the core is usually

too cool to produce acceptable plates and it takes one casting to raise the core to the desired temperature range.

As previously explained, a plate may be ejected at any time by the ejection station by actuation of button 540. The circuitry device is such that any rejected plate will not detract from the plates programmed to be produced and the counter will automatically compensate for the ejected plate.

Having thus described our invention what we claim is:

1. A stereotype plate casting and finishing machine comprising a casting station, a movable water-cooled core and a movable casting box in said casting station, said core and box together forming a vertically extending mold cavity into which molten metal may be poured, core rotation means for rotating said core and a cast plate to a substantially horizontal position, plate pusher means for pushing said plate from said casting station into a shaving station, a rotatable knife bar having a cutting saw thereon for severing a tail from a cast plate while in said shaving station, an ejection station, powered roller means for moving a severed tail from said shaving station into said ejection station, propeller means for moving a plate from said shaving station onto said powered rollers so that said plate may be carried to said ejection station, ejector means in said ejection station for ejecting severed tails from said casting machine and for ejecting defective plates from said casting machine, retractable ejection stop means for stopping a plate in said ejection station, inclined means for moving a plate by gravity from said powered roller means, a milling station wherein recesses are milled on the bottom side of said plates, and retractable safety stop means for preventing inadvertent movement of a plate from said incline means into said milling station.

2. A casting machine according to claim 1 wherein said core has water circulation passages therein, an inlet passage for the admission of circulating water and an outlet passage for the emission of circulating water from the interior of the core, a manifold extending substantially the length of said core connected to said inlet passage and a series of nozzles in said manifold connecting the interior of said manifold with the interior of said core and through which circulating cooling water passes.

3. A casting machine according to claim 2 wherein said inlet passage and said discharge passage are located at substantially one end of said core and said nozzles are spaced closer together at the end of said core in which said inlet and outlet passages are located than at the other end of said core to provide even cooling of said core when molten metal is poured into the mold cavity.

4. A plate casting machine according to claim 1 wherein said propeller means comprises a rotatable lug, a movable carriage on which said lug is mounted, and carriage drive means for moving said carriage longitudinally of said casting machine to move a cast plate from said shaving station after a tail has been severed therefrom.

5. A plate casting machine according to claim 4 wherein said carriage drive means is intermittently driven by said rotatable knife bar.

6. A plate casting machine according to claim 1 wherein said ejector means comprises a pivotable arm mounted in said ejection station between said shaving station and said incline means, arm pivot means controlled by said rotatable knife bar to cause said arm to pivot and to eject a severed tail from said machine.

7. A plate casting machine according to claim 6 having in addition a reject means controlling said arm pivot means to cause said arm to pivot to eject a defective cast plate.

8. A plate casting machine according to claim 1 wherein said safety stop means comprises two vertically re-

11

tractable stops positioned on said incline means before said milling station adapted to be moved up into the path of a plate moving down said incline means.

9. A plate casting machine according to claim 8 wherein said retractable stops are moved by milling drive means which also drives milling means in said milling station.

10. A stereotype plate casting and finishing machine according to claim 1 having in addition a chip disposal system extending beneath said shaving and milling stations for removing chips from said machine comprising a rotatable conveyor screw having a left-hand thread on one end of said screw and a right-hand thread on the other end of said screw, a conveyor trough positioned below said screw having an opening in the center thereof, a conveyor belt extending laterally of said machine and positioned beneath said screw and said opening for removing chips moved by said screw to said opening to one side of said machine.

11. A chip disposal means for a stereotype plate casting machine having a milling station and a shaving station comprising a conveyor screw extending parallel to the longitudinal axis of said machine and beneath said milling and shaving stations, left and right hand threaded

5

12

portions on said screw, a conveyor trough positioned beneath said screw and having an opening in the center thereof, and a conveyor belt extending laterally of said machine and positioned beneath said opening for removing chips from said screw to the side of said machine.
